(57) **CLAIM**

The ornamental design for a syringe cap, as shown and described.

DESCRIPTION

FIG. 1 is a perspective view of the syringe cap according to the present invention;

FIG. 2 is a front elevation view thereof, the rear elevation view being identical;

FIG. 3 is a top plan view thereof;

FIG. 4 is a bottom plan view thereof;

FIG. 5 is a right side elevation view thereof, the left side elevation view being identical;

FIG. 6 is an enlarged sectional view taken along line 6-6 of FIG. 2; and,

FIG. 7 is a reference view thereof showing the actual use thereof.

The portions shown in evenly spaced broken lines do not form part of the design.
